UNITED STATES PATENT OFFICE.

WILLIAM F. DRAPER AND GEORGE A. DRAPER, OF HOPEDALE, MASSACHUSETTS, ASSIGNORS TO GEORGE DRAPER & SONS, OF SAME PLACE.

SUPPORT FOR SPINNING-SPINDLES.

SPECIFICATION forming part of Letters Patent No. 378,877, dated March 6, 1888.

Application filed August 15, 1887. Serial No. 246,994. (No model.)

To all whom it may concern:

Be it known that we, WILLIAM F. DRAPER and GEORGE A. DRAPER, of Hopedale, in the county of Worcester and State of Massachusetts, have invented an Improvement in Supports for Spinning-Spindles, of which the following description, in connection with the accompanying drawings, is a specification, like letters on the drawings representing like parts.

10 In that class of spindles having a tapering pintle much trouble is experienced in securing a uniform fit between the tapering exterior of the pintle and the interior of the bolster having a tapering bore, makers of such spindles aiming at great accuracy of fit to thereby insure steadiness of rotation and equal distribution of wear of the parts.

Our invention consists in a bolster-case, a bolster placed therein loosely and having a 20 tapering interior, and a threaded step upon which the spindle rests and to which the said bolster is adjustably attached, combined with a locking device to hold the said bolster in adjusted position, as will be described.

25 Figure 1, in vertical section, shows a spindle-bearing and rail embodying this invention, the spindle shown in elevation having its whirl in section. Fig. 2 is a section of Fig. 1 below the dotted line $x-x$; and Fig. 3 is a modification showing the fibrous packing omitted from the bearing portion b .

The rail A, spindle B, having a sleeve-whirl, C, and the bolster-case D and nut E are and may be all as usual.

30 The spindle B has a tapering pintle, a , which it is desired shall always be supported uniformly and evenly at its sides by the interior side walls of the bolster b , the bore made in the bolster to form its interior lateral bearing-surface being the same taper as the pintle. The lower end or extremity of the pintle rests on the step c , the latter sustaining substantially the weight of the spindle, the tapering interior of the bolster fitting the tapering exterior of the pintle from the step c to a point 40 preferably above the band-pull. The adjustment between the bolster and step is made by or through the screw-thread e , by which the parts b and c are joined, the adjustment or 45 relative movements of the parts longitudinally being effected by the rotation of the bolster b , while the step portion c is restrained from rotation by a pin or projection, e' , in the case D, entering a notch, as e'' , in the step. By ro-

tating the portion b on or with relation to the 55 step c , the interior surface of the said portion b may be made to bear closely against the tapering exterior of the pintle and yet enable the end of the spindle to rest on the said step. We have provided the upper end of the portion b with a pin or projection, f , which cooperates with a suitable notch, as g , or vice versa, in the bolster-case, the said notches, of any desired number and more or less close together, and the pin or projection, constituting 65 a locking device to retain the parts in adjusted position. We have shown the portion b as provided with holes for oil, and the said portion b is shown as surrounded by a fibrous packing, as p , to thus enable the lateral bearing portion to move in the bolster-case and follow the pintle of the spindle in its vibrations; but we desire to have it understood that the 70 said fibrous packing may be omitted from the portion b , as in Fig. 3.

In order that the lateral bearing portion b of the bolster may be connected to the step, so as to move with the pintle and not move the step for like distance, we have so cut the screw-threads connecting the portion b with the step 80 as to leave considerable play between the threads.

We claim—

1. The bolster-case, the bolster b , placed therein loosely, and having a tapering interior, 85 and the threaded step upon which the spindle rests and to which the said bolster is adjustably attached, combined with locking devices to hold the said bolster in adjusted position, substantially as described.

2. The spindle, the bolster-case, and bolster held therein, made to constitute a lateral bearing portion, a step portion and means to connect them in an adjustable manner, combined with two pins or projections to restrain the 95 rotation of both the bolster and the step by the action of the spindle, yet permit the said parts to be adjusted one with relation to the other longitudinally when desired, as and for the purpose set forth.

In testimony whereof we have signed our names to this specification in the presence of two subscribing witnesses.

WM. F. DRAPER.
GEO. A. DRAPER.
